SLIDE LOOP

Filed Aug. 9, 1943

FIG. 4

George Henry Elwell INVENTOR.

UNITED STATES PATENT OFFICE

2,383,298

SLIDE LOOP

George Henry Elwell, New Haven, Conn., assignor
to Eastern Tool and Manufacturing Company,
Bloomfield, N. J., a corporation

Application August 9, 1943, Serial No. 497,908

2 Claims. (Cl. 24—73)

This invention relates to slide loops, combining the slide and the button loop in one structure.

With reference to the accompanying drawing, the Figure 1 illustrates an upright face view of the device secured upon a strap; Figure 2 illustrates the same view of the device, but without the strap; Figure 3 illustrates an upright rear view of the device with a pivotal bar in full line horizontal position, and dotted open position; Figure 4 illustrates an upright rear view of the body part of the device without the pivotal member; and Figure 5 is an enlarged side view in cross-section on the line 5—5 of Figure 2.

With more particular reference to the accompanying drawing, the numeral 1 designates the body part of the device with rounded edges and having within its face 2 an opening 3 communicating with a loop 4 adapted to receive and retain a button (not illustrated) insertible from the rear within the opening 3. The body part 1 bordering the opening 3 is provided with the integrally inturned teeth 5 rearwardly projecting therefrom. At both sides of the upper rear portion of the body unit 1 are integrally provided the brackets 6 and 7 bent in alignment, one with the other, in a common plane, spaced from and parallel with said rear, as illustrated by the Figure 4 to provide between the plane of said brackets 6 and 7 and the rear of said body part 1 a vertical passage 9 for the insertion of a strap S.

At the rear of the body part 1 is a pivotally movable part comprising the bar 10, pivotally secured by one end to the bracket 6 having the bore 8 by means of a suitable fastening pin 8' secured therethrough, the lower portion of the bar 10 at the opposite end thereof having the inwardly bent and backwardly extending clasp 11 in a plane parallelly spaced therefrom, while intermediate the length of the bar 10 is provided the inwardly bent flange 12 integral therewith.

In use, to admit the strap S within said vertical strap passage 9, the bar 10 is made to assume the dotted position shown in the Figure 3, then placing one side edge of the strap S within a bracket 6 or 7 and placing the other side edge thereof within the other of said brackets. With the strap S in proper alignment within the passage 9, the bar 10 may be lifted to its closed position, care being taken that the parallelly spaced parts of the clasp 11 straddle the adjacent bracket 7, thus securing the bar 10 to the brackets 6 and 7 so that its flanged portion 12 projects into the opening 3 and against the rear surface of the strap S to depress into contact with the teeth 5 along the lines S' shown in the Figure 1. To readjust the strap S within the

passage 9, the bar 10 may be released from the bracket 7 during the adjustment. The engagement between the clasp 11 and the bracket 7 maintains the bar 10 rigidly in its proper position, and the relative pulling stress between the button engaged device and the strap S cooperates to maintain the closed position of the bar 10.

While the device as illustrated shows a sheet-stock structure, yet in its manufacture the invention is not confined to such sheet-stock; for it is conceivable that the body part 1 thereof might be made of wire, if desired. Also the flange 12 may be provided with teeth in addition, or in place of, the teeth 5.

I claim:

1. A slide loop comprising a body and a part relatively movable therewith, the body having a flat face provided with an opening therethrough; side brackets provided by said body and spaced from the rear of, and parallel with, said face, said brackets extending toward one another and, with the rear surface of said body, providing a strap passage; a movable bar pivotally supported at one end by one of said brackets, and the bar at its opposite end being provided with means adapted to lock the bar against upward movement relative to the other of said brackets; a flange centrally provided at the lower edge of said bar, said central flange, in bracket connecting position of said bar, projecting into the upper portion of said opening; and a strap in a vertical plane within said passage and, in part, adapted to be rearwardly off-set into another vertical plane by said flange projected into said opening adjacent an edge thereof.

2. A slide loop comprising a body and a part relatively movable therewith, the body having a flat face provided with an opening therethrough; rearwardly bent teeth provided by the upper edge of said opening; side brackets provided by said body and spaced from the rear of, and parallel with, said face, said brackets extending toward one another and, together with the rear surface of said face, providing a strap passage; a movable bar pivotally supported at one end by one of said brackets, and the bar at its opposite end being provided with means adapted to lock the bar against upward movement relative to the other of said brackets; a flange provided at the lower edge of said bar, said flange, in bracket connecting position of said bar, projecting into the upper portion of said opening adjacent said teeth; and a strap positioned in a vertical plane within said passage and having a part rearwardly off-set into another vertical plane by said projected flange in said bracket connected position of said bar and in contact with said teeth.

GEORGE HENRY ELWELL.
